THROWING ROTOR SURROUNDED BY ROTARY ABUTMENT IMPACT SURFACE

Otto Müller, Paris, France, assignor to Ste Jaruza A. G. Chur, Zurich, Switzerland, a Swiss body

Application June 25, 1956, Serial No. 593,676

10 Claims. (Cl. 241—187)

This invention relates to impact crushers and has more particular reference to impact crushers of the type in which a rotor fitted with peripherally spaced hammers throws the products to be crushed upon an impact surface on which they break.

When impact crushers of the aforesaid type are used to crush sticky products, part of the crushed products adheres to the impact surface and progressively forms a layer which very substantially reduces the impact effect and consequently reduces the efficiency of the crusher.

One object of the present invention is to provide a novel and improved impact crusher of the type in which the products to be crushed are thrown onto an impact surface on which they break, wherein the impact surface is formed on a rotatable body with the impact surface surrounding the axis of rotation of the body and with the body so positioned with respect to the rotor of the impact crusher that the path of rotation of the impact surface intersects the trajectory path of the products thrown by the rotor, thereby reducing the sticking of products on the surface and insuring that the wear is the same on the entire area of the impact surface.

Another object of the present invention is to provide a novel and improved impact crusher, as characterized above, wherein means are provided for cleaning the impact surface of any products sticking thereon, including an element for scraping or brushing the impact surface and positioned to engage the impact surface as it rotates.

Another object of the present invention is to provide an impact crusher, as characterized above, including means for washing the impact surface as it rotates to remove any products sticking thereon.

Another object of the present invention is to provide a species of impact crusher, as characterized above, in which the impact surface of said body is an external surface.

Another object of the invention is to provide another species of impact crusher, as characterized above, in which the body is a hollow body with the rotor rotatably mounted therein and in which the impact surface is formed on the internal wall of the body.

A further object of the invention is to provide a novel and improved impact crusher, as characterized above, which is simple in construction, inexpensive to manufacture, and efficient in operation.

Other objects and advantages of the invention will appear in the following specification when considered in connection with the accompanying drawings, wherein:

Fig. 1 is a vertical sectional view of one embodiment of an impact crusher constructed in accordance with the present invention;

Fig. 2 is a vertical sectional view taken on the line 2—2 of Fig. 1;

Fig. 3 is a horizontal sectional view taken on the line 3—3 of Fig. 2;

Fig. 4 is a vertical sectional view of a modified form of impact crusher and showing the movable impact surface partly in full line; and

2

Fig. 5 is a horizontal sectional view taken on the line 5—5 of Fig. 4.

The present invention provides a novel and improved impact crusher having a movable impact surface and, in general, comprises a rotor carrying a plurality of peripherally spaced hammers for throwing the products to be crushed onto the impact surface; an impact surface formed on a rotatable body with the impact surface surrounding the axis of rotation of the body and with the body so positioned with respect to the rotor that the path of rotation of the impact surface intersects the trajectory paths of the products thrown by the rotor; cleaning means in the form of a brush or scraper or means for directing a stream of washing liquid for engaging the impact surface as it rotates and cleans the surface of any products sticking thereon.

The invention further contemplates that the impact surface formed on the rotating body may be formed on the external surface of the body or on the internal surface 20 of the body; in the latter case, the body is made hollow and the rotor is mounted therein for rotation about a horizontal axis.

Referring now to the drawings, there is illustrated in Figs. 1, 2 and 3, one embodiment of an impact crusher 25 constructed in accordance with the present invention. As there shown, the impact crusher comprises an elongated upright, hollow, open-ended housing or casing 10 mounted on a ball bearing support assembly, indicated generally at 11, for rotation about a vertical axis; a plurality of anvil or breaker plates 12 removably secured to the interior surface of the casing 10 and forming an impact surface 13; a rotor 14 carrying a plurality of peripherally spaced hammers 15 and having the ends of its shaft 16 journaled in suitable bearings 17 supported 30 by vertical support members 18, each carrying a scraping element 19 positioned to engage the impact surface 13 carried by the rotatable casing 10; a pipe 20 projecting down into the casing 10 and carrying a plurality of spray nozzles 21 positioned to direct a spray of wash liquid onto 40 the impact surface 13; and a hopper 22 for feeding the products to be crushed into the path of rotation of the hammers 15 carried by the rotor 14.

The hollow housing or casing 10 may be of any suitable shape and have its internal surface surrounding the 45 rotor lined with anvil plates forming an impact surface. As shown, the housing is generally spherical with its lower end portion made cylindrical, as indicated at 23, and having a flange 24 journaled in the ball bearing support assembly 11. The casing may be rotated by any suitable 50 means, such as a toothed crown 25 formed around its cylindrical lower end portion and driven by an endless screw 26. The generally spherically shaped impact surface 13 lining the casing 10 may be constructed in any suitable manner. It is shown as being formed of a plurality of anvil plates 12 removably secured to the casing, as by bolting, and having grooves formed therein providing cutting edges 27. The rotor 14, with its hammers 55 15, may be of any suitable construction and the hammers may be fixed or hinged on the rotor, or mounted 60 thereon in any suitable manner.

The rotor 14 may be rotated by any suitable means. As shown, the rotor shaft has a pulley 28 fixed thereon and connected to be V-belt driven by a drive pulley 29 on a shaft 30 driven by any suitable means (not shown). 65 The pulleys 28 and 29 and the V-belt are enclosed in a protective housing 31 mounted on the adjacent bearing support member 18. The bearing support members 18 may be of any suitable construction. They are shown as elongated flat plates having lateral flanges on their bottoms and having openings in their upper end portions in which the bearings 17 are fixedly mounted. The scraper or brush elements 19 may be of any suitable construction.

They are shown as being flat elongated members, each fixedly mounted on one of the support members 18 and each having a scraping edge having a configuration conforming to the external surface configuration of the impact surface 13 so that the scrapers can remove all products sticking to the impact surface as the surface rotates.

It should be noted that the support members 18 outline a space inside which the rotor turns, as well as two lateral spaces protected against the thrown products, and that the two scraper elements 18 are so positioned that sticky products received on the impact area by direct impact are removed as well as sticky products received on the opposite area by splashes.

The operation of the apparatus shown in Figs. 1, 2 and 3 is believed apparent.

The materials to be crushed are fed into the apparatus through the hopper 22 and fall by gravity into the path of movement of the hammers carried by the rotor adjacent the highest point of their movement. The material is partially crushed by the impact of the hammers and the parts not crushed by the impact of the hammers are violently thrown upon the impact surface 13, where they burst. The pieces of material then fall down and out of the crusher through the opening in the bottom of the casing.

Any sticky pieces which adhere to the impact surface are removed by the scraper elements 19 and/or the stream of wash liquid discharged through the nozzles in the pipe 29, as the impact surface is rotated. Thus, the products are always thrown upon a clean impact surface and the wear on the anvil plates making up the impact surface is uniform.

In Figs. 4 and 5, there is illustrated a modified form of impact crusher having a movable impact surface. As there shown, the apparatus comprises a stationary housing or casing 32; a roller 33 mounted in the housing 32 for rotation about a vertical axis and having an impact surface 34 formed on its external side walls; a rotor 14', carrying a plurality of peripherally spaced hammers 15', having the ends of its shaft 16' journaled in suitable bearings formed in the side wall of the housing 32 for rotation about a horizontal axis; a scraper element 35 secured to the side wall of the housing 32 and positioned to engage the impact surface 34 of the roller 33 as the roller rotates; a pipe 36 projecting downwardly into the housing 32 and carrying a plurality of spray nozzles 37 positioned to direct a spray of wash liquid onto the impact surface 34 of the roller 33; and a hopper 38 for feeding the products to be crushed into the path of rotation of the hammers 15' carried by the rotor 14'.

The casing or housing 32 may be of any suitable construction.

The roller 33 may be of any suitable construction and its external surface, on which the impact surface is formed, is in the form of a surface generated by the revolution of a line about the axis of rotation of the roller, i. e., it may be either cylindrical, convex, concave, or conical. As shown, the roller 33 is a hollow, spool-like, generally cylindrical member, and the side surface of the roller 33 is made convex. The impact surface 34 may be integral with the roller or formed in any suitable manner. As shown, the impact surface 34 is formed by a plurality of anvil plates 38 removably secured to the external surface of the roller, as by bolting, and having grooves formed therein providing cutting edges 39. The roller 33 has the ends of its shaft 40 journaled in the top and bottom walls of the casing 32, and the roller shaft has a pulley 41 fixed thereto and adapted to be driven by any suitable means (not shown).

The rotor 14', with its hammers 15', may be of any suitable construction and are similar to the corresponding parts shown in Fig. 1. The rotor 14' is driven as by means of a pulley 28' fixed on its shaft 16' and driven by any suitable means (not shown).

The scraper element 35 may be of any suitable con-

struction and is shown as comprising an elongated member having a securing flange along one edge by which it is secured to the side wall of the casing and having its outer free edge portion which engages the impact surface 5 conforming to the contour of the impact surface to scrape off any sticky products thereon as the surface rotates.

The pipe 36 is inwardly curved so that its nozzles will be positioned to project sprays onto the impact surface of the roller.

10 The operation of the modification shown in Figs. 4 and 5 is believed apparent. The materials to be crushed are fed into the apparatus through the hopper 22' and fall into the path of movement of the hammers. The material is thrown by the hammers onto the rotating impact surface of the roller 33, where it is crushed by impact and the broken pieces fall through the opening in the bottom of the casing below the rotor 14'. Any sticky pieces which adhere to the impact surface are removed by the scraper 35 and/or the wash liquid sprayed by the pipe 36.

15 From the foregoing, it readily will be seen that there has been provided a novel and improved impact crusher having a rotatable impact surface positioned to receive the products to be crushed on one area thereof as they are thrown thereon by the rotor and hammers and provided with means for removing any products which stick thereon so that a clean impact surface is continuously presented, thus insuring the efficiency of the apparatus and making the wear on the impact surface uniform.

20 While the impact surface shown in the modification illustrated in Figs. 1, 2 and 3 of the drawings has been shown to be generally spheric, obviously, it may be of any suitable shape such as cylindrical or conical.

25 Obviously, the invention is not restricted to the embodiments thereof herein shown and described.

30 35 What is claimed is:

1. In an impact crusher, a rotor mounted for rotation about a horizontal axis, said rotor including a plurality of peripherally spaced hammers, means including a hopper for gravity-feeding the products to be crushed into the path of movement of said hammers whereby said products will be thrown along trajectory paths extending outwardly from said rotor, a body rotatable about an axis extending perpendicularly with respect to the horizontal plane in which the axis of said rotor is located and having an impact surface formed thereon and surrounding its axis of rotation, said body being so positioned with respect to said rotor that the path of rotation of said impact surface of said body intersects the trajectory paths of the products thrown outwardly from said rotor, the construction and arrangement being such that the entire area of the impact surface as it rotates is brought into use so that the wear is the same on the entire area of the impact surface.

2. Apparatus as set forth in claim 1, wherein means are provided for cleaning said impact surface of any products sticking thereon including a spray member for directing a liquid spray against said impact surface, at a point in its path of rotation spaced from the point at which it intersects the trajectory paths of the products thrown thereagainst by said rotor.

3. Apparatus as set forth in claim 1, wherein said rotatable body is in the form of an elongated open-ended hollow body surrounding said rotor and with the internal side surface of said body forming said impact surface.

4. Apparatus as set forth in claim 3, wherein said hollow body rotates about an axis perpendicular to the axis of said rotor and wherein said impact surface is generally spherical.

5. Apparatus as set forth in claim 1, wherein said rotatable body is in the form of an elongated member positioned adjacent said rotor and with the external side surface of said body forming said impact surface.

6. Apparatus as set forth in claim 5, wherein said rotatable body is in the form of a generally cylindrical member having a convex side wall and wherein the convex

side wall of said rotatable body partially surrounds said rotor.

7. In an impact crusher, an elongated hollow open-ended rotatable casing mounted for rotation about a vertical axis, a rotor mounted within said casing for rotation about a horizontal axis, said rotor including a plurality of peripherally spaced hammers, a hopper for feeding the products to be crushed into the open end of said casing so that they fall along a defined path into the path of movement of said hammers adjacent the highest point of their movement, means for rotating said rotor at a speed sufficient to cause said hammers to throw said products on impact therewith onto the internal surface of said casing opposite the trajectory area of said rotor; a plurality of anvil plates on the internal wall of said housing forming an impact surface surrounding said rotor; and means for rotating said casing so that the entire area of said impact surface as it rotates will be brought into position to receive the products projected thereagainst by said hammers, whereby the wear on said anvil plates will be uniform.

8. Apparatus as set forth in claim 7, wherein means are provided for cleaning said impact surface of any products sticking thereon including a scraping element positioned to engage said impact surface at a point in its path of rotation spaced from the point at which it intersects the trajectory paths of the products thrown thereagainst by said rotor and a spray member for directing streams of washing liquid onto said impact surface.

9. In an impact crusher, a housing; a rotor carrying a plurality of hammers mounted within said housing for rotation about a horizontal axis; a generally cylindrical member having a convex side wall mounted within said

housing for rotation about a vertical axis, said generally cylindrical member having its side wall covered by anvil plates forming an impact surface and positioned so that said convex side wall partially surrounds said rotor; a hopper projecting into said housing and positioned to gravity-feed a stream of products to be crushed into the path of movement of said hammers; means for rotating said rotor at a speed sufficient to cause said hammers to throw said products on impact onto said impact surface of said cylindrical member; and means for rotating said cylindrical member so that the entire area of its impact surface as it rotates will be brought into position to receive the products thrown thereagainst by said hammers, whereby the wear on said anvil plates will be uniform.

10. Apparatus as set forth in claim 9, wherein means are provided for cleaning said impact surface of any products sticking thereto, including a scraping element positioned to engage said impact surface at a point in its path of rotation spaced from the point at which it receives the products thrown thereagainst by said rotor and a spray member for directing streams of washing liquid onto said impact surface.
